PLACER MINING MACHINE

Frank Tucker, Billings, Mont.

Application January 17, 1940, Serial No. 314,334

2 Claims. (Cl. 209—44)

The present invention relates to new and useful improvements in placer mining machines and has for one of its important objects to provide, in a manner as hereinafter set forth, an apparatus of this character embodying a novel combination and arrangement for rapidly and thoroughly separating the coarser portions of the material from the finer portions thereof.

Another important object of the invention is to provide a machine of the aforementioned character embodying novel means whereby small nuggets will be separated from the black sand and dirt and subsequently recovering or separating the black sand from the dirt.

Still another very important object of the invention is to provide a placer mining machine of the character set forth in the form of a unitary structure wherein all of the moving parts may be driven from a single source of power.

Other objects of the invention are to provide a placer mining machine which will be comparatively simple in construction, strong, durable, highly efficient and reliable in use and which may be manufactured at low cost.

All of the foregoing and still further objects and advantages of the invention will become apparent from a study of the following specifications, taken in connection with the accompanying drawings wherein like characters of reference designate corresponding parts throughout the several views, and wherein—

Figure 1 is a view in side elevation of a placer mining machine constructed in accordance with the present invention.

Figure 2 is a view in vertical longitudinal section through the rear portion of the apparatus.

Figure 3 is a view in vertical longitudinal section through the forward portion of the apparatus.

Figure 4 is a cross sectional view, taken substantially on the line 4—4 of Figure 2.

Figure 5 is a cross sectional view, taken substantially on the line 5—5 of Figure 2.

Figure 6 is a cross sectional view through the rotary screen and adjacent parts.

Figure 7 is a cross sectional view through the stacking conveyor, taken substantially on the line 7—7 of Figure 1.

Figure 8 is a view in vertical longitudinal section through an intermediate portion of the riffle.

Referring now to the drawings in detail, it will be seen that the embodiment of the invention which has been illustrated comprises an elongated frame structure which is designated generally by the reference numeral 1, said frame structure being mounted on rollers 2. Mounted for vertical swinging adjustment on the forward end of the frame structure 1 is an endless stacking conveyor 3. The conveyor 3 is adjusted by means including cables 4 traveling over pulleys 5

and wound on a manually operable drum 6 mounted on the forward end of the frame structure 1. Mounted in the rear end portion of the frame structure 1 is a suitable power plant 7. A belt and pulley drive 8 operatively connects the conveyor 3 to the power plant 7. Any suitable means may be employed for controlling the operation of the conveyor 3.

Rotatably mounted in the upper portion of the frame structure 1 is what may be referred to as a barrel which is designated generally by the reference numeral 9. The barrel 9, it will be observed, is inclined toward its forward end and the rear portion of said barrel is in the form of a metallic cylinder 10. The forward portion of the barrel 9 is in the form of a cylindrical screen 11. Rollers 12 (see Fig. 5) rotatably support the barrel 9 in the frame structure 1.

Mounted in the barrel 9 is a plurality of spirally extending fins 13. The cylinder 10 is provided with four of these fins 13. However, but two of the fins extend through the rotating screen 11, the remaining two terminating at the forward end of the cylinder 10. The rear or intake end of the cylinder 10 is provided with an internal flange 14. This is shown to advantage in Figure 2 of the drawings. A suitable belt and pulley drive 15 (see Figs. 2 and 5) operatively connects the barrel 9 to the power plant 7.

Mounted on the upper, rear portion of the frame structure 1, adjacent the rear end of the barrel 9, is a hopper 16. A grizzly 17 in the form of a plurality of spaced, inclined rails or bars is provided in the hopper 16. Mounted in the rear end portion of the frame structure 1 is a comparatively short, inclined endless conveyor 18 which receives the material from the hopper 16 and deposits said material in the rear end portion of the barrel 9. Mounted longitudinally on one side of the frame structure 1 is an inclined endless conveyor 19 which is adapted to receive the comparatively large rocks, etc., which are separated from the material by the grizzly 17 in the hopper 16 and discharge said rocks, etc., on the stacking conveyor 3. A belt and pulley drive 20 operatively connects the conveyor 19 to the power plant 7. Then, a belt and pulley drive 21 actuates the conveyor 18 from the drive 20.

Mounted beneath the rotating cylindrical screen 11 is a substantially trough shaped vibrating screen 22. Guards 23 are provided adjacent the lower side portions of the revolving screen 11 for preventing the material therefrom from spilling or dropping over the sides of the vibrating screen 22. The vibrating screen 22 is suspended on hangers 24. The screen 22 is vibrated by the power plant 7 through a suitable drive 25 (see Fig. 1). A chute 26 on the forward end portion of the frame structure 1 is adapted to receive the coarser materials removed by the

screens 11 and 22 and deposit said materials on the conveyor 3.

Mounted in the frame structure 1 beneath the vibrating screen 22 is a rearwardly inclined trough 21. Suspended in the frame structure 1 beneath the trough 21 and adapted to receive the material therefrom at its rear end is a sluice 28. Riffles 29 are mounted in the sluice 28. Referring now to Figure 8 of the drawings, it will be observed that the riffles 29 are in sections or units on plates 30 which are removably secured in position by bolts 31. A suitable drive 32 from the power plant 7 vibrates the sluice 28. In the forward end portion of the sluice 28 is a screen 33 (see Fig. 3). Mounted beneath the screen 33 is a receptacle 34 for receiving the black sand which is separated from the dirt by the screen 33, said dirt passing over said screen to the conveyor 3.

It is thought that the operation of the apparatus will be readily apparent from a consideration of the foregoing. All of the moving parts are driven by the single power plant 7. The material is placed in the hopper 16 in any suitable manner and the large rocks, etc., are separated therefrom by the grizzly 17, being deposited thereby on the conveyor 19. As hereinbefore explained, these large rocks, etc., are deposited by the conveyor 19 on the conveyor 3 by which they are carried away from the machine and discharged. A perforated pipe 35 from a suitable source of supply discharges water into the barrel 9. The material which passes through the grizzly 17 drops from the hopper 16 to the conveyor 18 by which it is deposited in the rear end portion of the inclined, rotating barrel 9. This material is moved by gravity and the spiral fins 13 toward the lower end of the inclined barrel 9, passing through the cylindrical screen 11. The revolving cylindrical screen 11 now removes the coarser portions of the material and deposits them on the conveyor 3 through the medium of the chute 26. The material which is fine enough to pass through the mesh of the revolving cylindrical screen 11 drops into the inclined, vibrating screen 22 and the coarser materials are again removed and deposited on the conveyor 3 through the medium of the chute 26. The materials passing through the vibrating screen 22 drop into the trough 21 and are deposited thereby in the rear end portion of the sluice trough 28, as at 36 (see Fig. 2). These materials are then moved forwardly by the vibrating sluice 28 and the nuggets are separated and retained by the riffles 29. The remaining materials, comprising black sand and dirt, then pass over the screen 33 through which the black sand drops into the receptacle 34, the dirt passing on to the conveyor 3. The water passing over the riffles 29 will pass over the screen 33 and the heavier fine material will pass through the screen into the receptacle 34. The screen 33 forms a continuation of the bottom of the sluice and the upper edges of the receptacle are close to the bottom of the screen and accordingly the water passing through the sluice will enter the receptacle and create a level so close to the screen that the tailings will be washed over the screen onto the tailings conveyor 3. It will be understood that this action will depend on a proper volume of water passing through the sluice and the water will spill over the rear wall of the receptacle before reaching the conveyor. Suitable supporting brackets 37 are provided on one side of the frame structure 1 for the conveyor 19. The forward end of the conveyor 19

projects beyond the frame structure 1 and suitable braces 38 are provided therefor.

It is believed that the many advantages of a placer mining machine constructed in accordance with the present invention will be readily understood and although a preferred embodiment of the device is as illustrated and described, it is to be understood that changes in the details of construction and in the combination and arrangement of parts may be resorted to which will fall within the scope of the invention as claimed.

What is claimed is:

1. A placer mining machine comprising, in combination, a frame structure, a tailings conveyor on one end of said frame structure, a hopper for the reception of material, on the other end of the frame structure, a grizzly in said hopper for removing the oversize from the material, a conveyor or the frame structure for conveying the oversize from the grizzly to the tailings conveyor, an inclined barrel, including a foraminous lower portion, rotatably mounted on the frame structure, means for conveying the material from the hopper into said barrel, a vibrating screen mounted beneath the foraminous portion of the barrel for receiving the material screened therethrough, said barrel and screen both having a discharged end in superposed relation, common means for receiving tailings from the barrel and the vibrating screen and discharging the same onto the tailings conveyor, means for receiving the material from the vibrating screen and recovering the values therefrom and also arranged to deposit tailings onto the tailings conveyor, all of the tailings being discharged onto the tailings conveyor in the direction of travel of the tailings conveyor, and means for actuating the conveyors, the barrel, the first named means and the vibrating screen.
2. A placer mining machine comprising, in combination, an elongated frame structure, a hopper for the reception of material, mounted on one end portion of said frame structure, a grizzly in the hopper for removing oversize from the material, an endless conveyor mounted longitudinally on the frame structure for receiving the oversize from said grizzly, an inclined rotary barrel mounted longitudinally on the frame structure and including a foraminous lower portion, an endless conveyor mounted on the frame structure for conveying the material from the hopper into said barrel, a vibrating screen mounted beneath the foraminous portion of the barrel for receiving material screened therethrough, a return trough mounted beneath the vibrating screen for receiving the material therefrom, a vibrating sluice mounted beneath the trough for receiving the material and recovering the values therefrom, a receptacle at the lower end of the sluice having a foraminous cover forming a continuation of the bottom of the sluice and through which fine values are deposited into the receptacle, said sluice and cover extending beyond the receptacle, a conveyor mounted on the other end of the frame structure for receiving tailings from said sluice and the oversize from the first named conveyor, a chute mounted on said other end of the frame structure for conveying tailings from the barrel and the vibrating screen to the third named conveyor, all of the tailings being discharged onto the tailings conveyor in the direction of travel of the tailings conveyor, and means for actuating the conveyors, the barrel, the vibrating screen and the sluice.
